UNITED STATES PATENT OFFICE.

FREDRICK ALBERT THURSTON, OF LYNN, MASSACHUSETTS

MACHINE FOR BUFFING ARTICLES OF SHEET MATERIAL.

1,047,335.

specification of Letters Patent.

Patented Dec. 17, 1912.

Application filed March 12, 1912. Serial No. 683,229.

To all whom it may concern:

Be it known that I, FREDRICK ALBERT THURSTON, a citizen of the United States, residing at Lynn, in the county of Essex, 5 and State of Massachusetts, have invented new and useful Improvements in Machines for Buffing Articles of Sheet Material, of which the following is a specification.

This invention relates to a machine for 10 buffing articles of sheet material, the same being particularly adapted to buff counters and toe caps for boots and shoes. Furthermore, said counters, having been skived on another machine, are then adapted to be 15 operated upon by the machine of this invention to simultaneously buff the opposite ends of said counter.

The invention consists in the combination and arrangement of parts set forth in the 20 following specification and particularly pointed out in the claims thereof.

Referring to the drawings: Figure 1 is a 25 partial plan view of the machine of my invention, the same being broken away to save space and the mechanism for automatically feeding counters to the buffing instrumentalities being removed. Fig. 2 is a detail section of the buffing wheel, brush and rotary carrier. Fig. 3 is a sectional elevation taken on line 3—3 of Fig. 1, with the 30 machine for feeding the counters partly in elevation and partly in section in connection therewith. Fig. 4 is a detail plan view of the mechanism for feeding the counters and a counter shown in connection therewith. Fig. 5 is a detail section taken on line 5—5 35 of Fig. 4. Fig. 6 is an elevation of the buffing instrumentalities viewed in the direction of the arrow *a*, Fig. 3, the mechanism for 40 feeding the counters being removed and the counter being shown in the position it would assume when buffed at opposite ends simultaneously by the buffing instrumentalities, the work-support being indicated in dotted 45 lines. Fig. 7 is a detail view of a collar. Fig. 8 is a detail section taken on line 8—8 of Fig. 6.

Like numerals refer to like parts throughout the several views of the drawings.

50 In the drawings, 10 is the rotary carrier roll, 11 is the buffing roll and 12 is a rotary brush.

The carrier roll 10 is provided with a series of matrices 13, 13 fastened by screws 55 14' to the roll 10 and forming, in effect, a portion of its periphery. Said matrices are

each provided with a recess 14 which is of such shape as to receive one end of a counter 15 (see Figs. 2 and 6). The matrices 13 are provided with a series of ports 16, 60 16 which each communicate, respectively, with a passage 17. The roll 10 is rotatably mounted upon a hollow stationary shaft 18 and is rotated by a disk 19 to which it is connected by pins 20. Said carrier roll is 65 prevented from moving longitudinally of the stationary shaft 18 by the disk 19 and also by a collar 21 fastened by a screw 22 to the stationary shaft 18. The disk 19 is fastened to a sleeve or hollow shaft 23 70 through which the stationary shaft 18 extends and said sleeve is rotatably mounted in bearings 24, 24 on an auxiliary frame 25 which, in its turn, is supported upon rods 26, 26, said rods being supported upon a 75 main frame 27. (See Fig. 3.)

The auxiliary frame 25 is adapted to be slid along the rods 26, 26 and locked in position by set-screws 28, 28. A rotary motion is imparted to the sleeve 23 in the direction 80 of the arrow *b* (Fig. 2) by a gear 29 (Fig. 6).

Air is exhausted from the ports 16, 16 through the passages 17 and through the passage 30 extending longitudinally through the shaft 18. A port 31 is supplied in said 85 shaft with which the different passages 17 communicate as the carrier roll 10 is rotated and a pipe 32 is connected to the stationary shaft 18 (Fig. 6) and from thence extends to an exhaust pump (not shown in the 90 drawings) whereby the air may be exhausted through the passages 30 and 17 from the ports 16, 16 so as to hold a counter 15 in the recesses 14 while said counter is passing beneath and in contact with the periphery of 95 the buffing roll 11, and with the rotary brush 12. Another port 33 is provided in the periphery of the stationary shaft 18 and extends longitudinally thereof through the collar 21 at the right hand end of the shaft 100 18, as viewed in Fig. 6.

The buffing roll 11 is fast to a shaft 34 which is rotatably mounted in bearings 35, 35 on a rocker frame 36. Said rocker frame is mounted upon a pivotal rod 37 fast to the 105 auxiliary frame 25, the outer or free end of said frame 36 containing the bearings 35, 35 and said bearings being interposed between two pairs of springs 38 and 39 (see Fig. 6). The upper spring 38 at its lower 110 end bears against the bearing 35 and at its upper end it bears against a washer 40, said

washer and spring being contained within a cylindrical boss 41 on the auxiliary frame 25. A set-screw 42 bears against the washer 40 and has screw-threaded engagement with the cap 43 which, in turn, has screw-threaded engagement with the boss 41 and is locked in position by a set-nut 44, so that by turning the screw 42 more or less tension can be placed upon the spring 38. The lower spring 39 (Fig. 6) is contained within a boss 45, also a part of the auxiliary frame 25. These springs are arranged in pairs, as illustrated in Fig. 6, the upper spring 38 tending to hold the rocker frame 36 downwardly so as to bring the buffing roll 11 against the counter 15 as it is carried along beneath said buffing roll by the carrier roll 10, and the spring 39 acting in opposition to said spring 38 and tending to move the rocker frame, with the buffing roll thereon, upwardly and away from the carrier roll 10.

A rotary motion is imparted to the buffing roll 11 by a pulley 46 fast to the shaft 34, to which shaft said buffing roll is fastened, and said pulley is rotated by means of a belt 47 which, in turn, is actuated by a pulley 48 fast to the main driving shaft 49 (see Fig. 3).

It will be noted by reference to Fig. 2 that the carrier roll 10 is rotated in the direction of the arrow *b*, while the buffing roll 11 is rotated in the direction of the arrow *c*—that is, said rolls are rotated in opposite directions and the buffing roll 11 is rotated at greater speed than the carrier roll 10. As the counter is carried along by the carrier roll 10 in the direction of the arrow *b* after passing the buffing roll and having been buffed on the ends thereof, it is brought into contact with the rotary brush 12 which rotates in the direction of the arrow *d* and by said brush the dust is removed from the surface of the counter.

The brush 12 is fast to a shaft 50 which is journaled to rotate in bearings 51, 51 forming a part of a rocker frame 52 which is pivoted upon the rod 37 and is supported at its free end by a rod 53 which has screw-threaded engagement with a nut 54 located above and bearing upon the rocker frame 36 (see Fig. 3), said rod 53 also having screw-threaded engagement with a nut 55 which bears against the under side of the rocker frame 36, so that by turning the nuts 54 and 55 in the proper direction, the rocker frame 52, with the shaft 50 and rotary brush 12, may be raised and lowered as desired and moved toward or away from the periphery of the carrier roll 10. This adjustment is particularly for the purpose of setting the brush in the proper position and also for adjusting the same as it wears in use so as to brush the surface of the counters as they are passed into contact therewith by the carrier roll 10. A rotary motion is im-

parted to the shaft 50 and to the brush 12 by a pulley 56 fastened to the shaft 34 and connected by a belt 57 to a pulley 58, the pulley 58 being fastened to the shaft 50.

The counters 15 are placed upon the work-support 59 one by one and fed between the buffing roll 11 and carrier roll 10 by mechanism illustrated in Figs. 3 and 4 and consisting of a slide 60 guided on rods 61 fast to the frame 27 and to which a reciprocatory motion is imparted by a lever 62 pivoted at 63 to the frame 27, a rocking motion being imparted to said lever in one direction by a spring 64 and in the opposite direction by a cam 65 fast to a shaft 66 to which shaft a rotary motion is imparted by suitable mechanism (not shown in the drawings). The periphery of the cam 65 bears against a roll 67 journaled upon the lever 62.

A T-shaped member 68, constituting a pusher, is fastened to the slide 60 by a screw 69 which projects through a slot 70 in the T-shaped portion 68 of the pusher and has screw-threaded engagement with the slide 60. The arms 71, 71 of the T-shaped member 68 each has a holder 72 fastened thereto by means of screws 73, 73, said holders being adjustable longitudinally of the arms 71, 71 and fastened in place by said screws 73, 73. Each of the holders 72 has mounted thereon a finger 74 pivoted at 75 to an inverted U-shaped bearing 76. The bearing 76 is fastened rigidly to the holder 72 and a spring 77 is connected at one end to the bearing 76 and at the other end to the finger 74, so that the forward end of said finger 74 is held with a yielding pressure against the upper surface of the work-support by the spring 77. Thus, as the finger 74 wears at its forward end by frictional contact with the upper surface of the work-support 59, the spring 77 will cause said finger 74 to tip upon the pivot 75 and thus always bring the forward end of said finger to bear against the upper surface of the work-support 59, so that the thin edge of the counter 15 cannot get between the finger 74 and the upper surface of the work-support and cause inaccuracy or failure in the feeding operation.

By reference to Figs. 1, 3 and 6, it will be seen that the recesses 14 open out of the end of the carrier roll 10.

As hereinbefore set forth the complete machine of this invention is adapted to simultaneously buff opposite ends of the counter. The drawings particularly illustrate the mechanism which buffs the left-hand end of the counter as it passes through the machine, but in Fig. 6 in dotted lines is also illustrated a portion of the machine which buffs the right hand end of the counter—that is, it illustrates in dotted lines the carrier roll and the buffing roll 130

associated therewith. The two parts of the machine, that is, the one that buffs the left hand end of the counter and the one that buffs the right hand end of the counter are substantially alike, except that they are arranged as right and left—that is, at one end of the machine, namely, the left hand end, as illustrated in Fig. 6, the buffing roll and the carrier roll are at the right of the mechanism which drives them, while in the other end of the machine, namely, the right hand end, the buffing roll and the carrier roll are located at the left of the mechanism which drives them.

15 In order to adapt the machine to simultaneously buff the opposite ends of counters of different lengths, the auxiliary frames 25 are made adjustable upon the rods 26, so that the buffing and carrier rolls, together with the rotary brushes, may move toward or away from each other to accommodate short or long counters respectively.

The general operation of the mechanism hereinbefore specifically described is as follows: The counters are placed upon the work-support 59 one by one in front of the pusher fingers 74, 74 as illustrated in Figs. 3 and 4. The mechanism having been started by throwing in a suitable clutch (not shown in the drawings, but in a manner well known to those skilled in this art) the counter is fed forward between the buffing rolls and the carrier rolls by means of the slide 60, lever 62 and cam 35 65. The mechanism is so timed that one of said counters is fed to the carrier roll beneath the buffing roll for each of the recesses 14, 14 in the periphery of said carrier roll. The exhaust causing a vacuum in the ports 16, 16, said counters will be held in the respective recesses as they pass beneath the buffing roll and into contact with the brush.

As soon as the counter has passed by the brush, air will enter the passage 17 and the 45 vacuum passage 30 will be shut off from the passage 17 so that the counter will no longer be held within the recess and will drop into a suitable receptacle as the carrier rotates in the direction of the arrow *b* (Fig. 2). This operation takes place with each of the counters held in the different recesses upon the periphery of the carrier roll as it is rotated, first the vacuum causing the counter to be held down upon the 55 periphery of the carrier roll while it is being burnished and brushed and subsequently the vacuum being broken the air rushes in through the port 33 and through the passage 17 and ports 16, so that the counter 60 is released from the periphery of the carrier roll and drops into the receptacle provided therefor. During this feeding of the counter, it will be understood that the buffing roll 11 is rotated at higher speed than 65 the carrier roll and in the opposite direc-

tion, as indicated by the arrows *c* and *b*, respectively, and the comparatively rough surfaces of the ends of the counter are smoothed off by the buffing rolls, said buffing rolls also being yieldingly pressed against the surface of the counter by the springs 38, so that the general form in cross sectional contour of the counter will be preserved, the machine acting only to smooth the same upon its surface, but not to change its shape, as would result if the buffing rolls were rigidly mounted instead of yieldingly supported.

70 After having been buffed, as hereinbefore set forth, the rotary brush 12 brushes the dust off of the surface of the counter and the same is then released from the periphery of the carrier roll and dropped into a suitable receptacle.

Having thus described my invention, what I claim and desire by Letters Patent to secure is:

1. A machine for buffing articles of sheet material having, in combination, a pair of feed rolls, one of said rolls having abrasive material upon its periphery and constituting a buffing roll, a stationary shaft upon which the other roll is rotatably mounted, said shaft having an air exhaust passage and an air supply passage therein, said passages opening out of the periphery of said shaft, said last-named roll having ports in its periphery and a passage therein leading from said ports and adapted to alternately communicate with said air exhaust and supply passages. 95

2. A machine for buffing articles of sheet material having, in combination, a pair of feed rolls, one of said rolls having abrasive material upon its periphery and constituting a buffing roll, a stationary shaft upon which the other roll is rotatably mounted, said shaft having an air exhaust passage and an air supply passage therein, said passages opening out of the periphery of said shaft, said last-named roll having a recess in its periphery adapted to receive one of said articles and having ports leading out of said recess into a passage therein which is adapted to alternately communicate with said exhaust and air supply passages. 110

3. A machine for buffing articles of sheet material having, in combination, a pair of feed rolls, one of said rolls having abrasive material upon its periphery and constituting a buffing roll, a stationary shaft upon which the other of said rolls is rotatably mounted, said shaft having an air exhaust and an air supply passage therein, said passages opening out of the periphery of said shaft, said last-named roll having a series of passages therein, each of said passages, respectively, communicating with a series of ports in the periphery of said roll and 125

adapted to alternately communicate with said exhaust and supply passages.

4. A machine for buffing articles of sheet material having, in combination, a pair of feed rolls, one of said rolls having abrasive material upon its periphery and constituting a buffering roll, a rocker frame upon which said buffering roll is rotatably mounted, a pair of springs between which the free end of 10 said rocker frame is interposed and means to hold one of said articles in the periphery of the other of said rolls.

5. A machine for buffing articles of sheet material having, in combination, a pair of feed rolls, one of said rolls having abrasive material upon its periphery and constituting a buffering roll, the other roll having ports 15 in its periphery and constituting a carrier

roll for one of said articles, means to exhaust the air from said ports, mechanism 20 adapted to impart a rotary motion to said rolls, a rotary brush adjacent to the periphery of said carrier roll and adapted to brush said articles as they pass out of contact with said buffering roll, a rocker frame upon 25 which said brush is rotatably supported and means to adjust said rocker frame to move said brush toward or away from the periphery of said carrier roll.

In testimony whereof I have hereunto set 30 my hand in presence of two subscribing witnesses.

FREDRICK ALBERT THURSTON.
